Letters Patent

dated June 3, 1868.

The state of art referred to in these Letters Patent and making part of the same is a sawing or planing machine for the wood of the sawing tree, and consists of the machine for sawing, Eye wood

The principal parts of the machine consist of a sawing saw, a carriage and a seat. The sawing saw is placed on the surface or circumference of a wheel winding in a spiral direction in manner of a screw round the wheel, so that as it performs a cutting motion it advances with the edge of the end of the wood as the saw may be said to be under the surface of the wheel, contracting towards the center, but progressing outwards in the cut. The carriage is for the purpose of supporting the seat and also for the purpose of supporting the end of the wheel against the periphery of the saw. The machine is designed to be used convenient in constructing the parts performed by a ratch wheel and cage advancing the stick of wood in a parallel direction with the cut or at right angles with the face of the saw.
